UNITED STATES PATENT OFFICE.

THEODORE J. NICHOLS, OF BELLEVUE, TEXAS, ASSIGNOR OF ONE-HALF TO JOHN S. NICHOLS, OF BELLEVUE, TEXAS.

CARBURETER.

1,156,924.

Specification of Letters Patent.

Patented Oct. 19, 1915.

Application filed March 9, 1915. Serial No. 13,187.

To all whom it may concern:

Be it known that I, THEODORE J. NICHOLS, a citizen of the United States, residing at Bellevue, in the county of Clay and State of Texas, have invented a new and useful Carbureter, of which the following is a specification.

The present invention appertains to carbureters, and aims to provide a novel and improved carbureter adapted for use in connection with internal combustion engines, and being of novel construction whereby the air is drawn through the gasoline or liquid fuel to vaporize the fuel and thereby provide a thorough and proper mixture of the air and fuel.

It is also within the scope of the invention to provide a carbureter improved generally in its construction and details, to enhance the utility thereof, the carbureter being comparatively simple and inexpensive in construction, and being thoroughly efficient and practical in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a vertical central section of the improved carbureter. Fig. 2 is a horizontal or cross-section of the carbureter taken on the line 2—2 of Fig. 1.

The present carbureter comprises an upright casing 1 having integral convexed top 2 provided with an upstanding tubular extension 3 providing the outlet of the carbureter, which is adapted to be bolted or otherwise secured to the intake manifold 4 of the engine. The casing 1 is provided with a removable bottom or lower end 5 threaded therein, and the bottom 5 is preferably provided with a pet cock 6 whereby the casing 1 may be drained whenever desired.

The top 2 of the casing is provided at one side of the extension or outlet 3, with an upstanding boss 7, through which an upright air inlet pipe 8 extends, the pipe 8 being slidable through the boss 7, and a gland nut 9 being threaded upon the boss 7 for compressing the packing 9^a against the pipe 8 for providing a fluid tight joint to prevent leakage. The upper end of the pipe 8 projects slightly above the boss 7 and nut 9, and the lower end of the pipe 8 is provided with a horizontal or angularly extending perforated nozzle 10 intersecting the axis of the casing 1 and located adjacent the bottom 5 of the casing. In other words, the nozzle 10 is located diametrically of the casing at the lower end thereof, the pipe 8 being disposed adjacent one side wall of the casing, and the nozzle 10 projecting to the opposite side wall. The end of the nozzle 10 is closed, and the side walls of the nozzle are provided with the apertures or perforations to allow the air to flow from the pipe 8 and nozzle 10 into the casing 1.

The outer or upper end of the pipe 8 is provided with a check valve, and to this end a plug 11 is threaded into the upper or outer end of the pipe 8, and is provided with an inner beveled valve seat 12 and air inlet apertures 13 extending from the valve seat 12 to the outer or upper side of the plug 11. A valve stem 14 is slidable through the plug 11 between the apertures 13, and carries a beveled valve 15 coöperating with the seat 12. A coiled wire expansion spring 16 is disposed around the stem 14 between the plug 11 and a nut 17 threaded upon the outer or free end of the stem 14 for normally seating the valve 15 to close the apertures 13, whereby the air suction will unseat the valve 15 against the tension of the spring 16 to allow the air to enter the casing 1 proportionately to the suction created by the engine.

The gasoline or fuel inlet of the casing 1 embodies a hollow coupling or member 18 provided with an upper removable screw cap or closure 19, and a lower nipple 20 for the attachment of the gasoline or fuel pipe leading to the tank or other source of fuel sup-

ply. The member 18 is provided with a valve seat 21 at the base of the nipple 20 or at the upper end of the duct which extends through the nipple, and the member 18 is also provided with a lateral branch or nipple 22 threaded through or otherwise engaged to that side of the casing 1 opposite the pipe 8. The member 18 is located between the upper and lower ends of the casing or at a point spaced sufficiently above the air nozzle 10.

A float lever 23 extends from within the member 18 through the branch 22 thereof into the casing 1 and is fulcrumed within the branch or nipple 22 by means of a fulcrum pin 24 engaged through the sides of the branch 22. The arm of the lever 23 within the casing 1 is secured to a cork or similar float 25 by means of a screw or other securing means 25^a, and the other arm of the lever 23 within the inlet member 18 carries a needle valve for controlling the inlet of gasoline. Thus, the needle valve 26 which coöperates with the valve seat 21 has its shank pivoted to an adjusting screw 27 which is threaded through the respective end of the float lever 23, whereby the needle valve 26 may swing or adjust itself to seat properly upon the seat 21 for closing the gasoline inlet through the nipple 20. The float 25 is of U-shape, and the lever 23 is attached to the intermediate portion of the float, whereby the float may stand astride the pipe 8, and whereby the pipe 8 passes through the slot of the float. The float thus occupies a suitable space within the casing 1, and projects to the opposite sides of the pipe 8 without interfering with the pipe.

A screen or diaphragm 28 is secured within the casing 1 between the ends thereof and at a point suitably above the float 25, and the pipe 8 extends through the screen 28. The office of the screen is to diffuse the upwardly flowing air and vapor, whereby the air and vaporized fuel will be properly admixed to provide the combustible mixture.

The carbureter is equipped with a second or auxiliary air inlet, and to this end a short pipe section or tubular member 29 is threaded or otherwise engaged through that wall of the extension or outlet 3 opposite the pipe 8, and is provided at its outer or free end with a check valve similar to the check valve carried by the pipe 8. Thus, a plug 30 is threaded or otherwise engaged into the end of the pipe section 29, and is provided with an inner bevel valve seat 31 and inlet apertures 32 leading from the valve seat to the outer side of the plug 30. A valve stem 33 is slidable through the central portion of the plug 30 and carries a beveled valve 34 coöperable with the seat 31. The valve 34 is drawn toward its seat by means of a coiled wire expansion spring 35 surrounding the

valve stem 33 and bearing at one end against the plug 30 and at its other end against a nut 36 threaded upon the stem 33. The valve 34 will be unseated by the suction, to admit an auxiliary supply of air into the intake conduit or manifold, so that the auxiliary supply of air will mix with the carbureted air flowing upwardly through the extension or outlet 3 of the carbureter, and whereby a saving of fuel is accomplished, as well as increasing the efficiency of the engine.

In operation, air will be drawn through the carbureter by the suction created during the suction strokes of the engine pistons, and this will draw the air into the pipe 8, and the air will be drawn out of the apertures or perforations of the air nozzle 10 so as to flow upwardly through the gasoline or fuel. The air thus flowing through the fuel will vaporize the fuel and the vaporized fuel will be carried upwardly with the air, through the screen 28, which serve to diffuse the mixture for properly commingling the air and fuel. This screen 28 will also prevent foreign particles from being drawn into the engine with the carbureted air, and which will prevent or reduce to a minimum the formation of soot or carbon within the cylinders.

The flow of carbureted air is controlled by means of a throttle valve 37 pivoted within the outlet extension 3 of the carbureter.

The level of the gasoline or fuel is maintained at a predetermined point within the casing 1, it being noted that when the fuel rises to a predetermined level within the casing 1, the float 25 will be lifted, and this will swing the lever 23 to thereby lower and seat the valve 26 for stopping the further flow of gasoline into the carbureter. When the gasoline level lowers, the float 25 will be lowered, and this will unseat the valve 26 momentarily until the gasoline again reaches the normal level.

It is to be noted that the air in being drawn upwardly through the gasoline will pass around the valve 25, and this will assist in the proper vaporization of the fuel. Furthermore, the float is carried within the main chamber of the carbureter, so that a separate float chamber is not necessary.

What is claimed is:

A carbureter comprising an upright casting having an upper outlet and a fuel inlet member at one side, an air inlet pipe slidable through the top of the casting and extending downwardly therein adjacent that side of the casting opposite the fuel inlet member, the lower end of the air inlet pipe having an apertured nozzle projecting to the opposite side of the casting, a U-shaped float within the casting above said nozzle and

standing astride said pipe, a lever fulcrumed within the fuel inlet member and having one arm attached to the intermediate portion of the float, and a valve carried by the other arm of the lever and arranged to control the inlet of fuel into the fuel inlet member.

5 In testimony that I claim the foregoing

as my own, I have hereto affixed my signature in the presence of two witnesses.
